UNITED STATES PATENT OFFICE.

FRED MATHEWS, OF CHICAGO, ILLINOIS.

RUNNING-BOARD RETAINER.

1,209,741.

Specification of Letters Patent. Patented Dec. 26, 1916.

Application filed October 19, 1916. Serial No. 126,474.

To all whom it may concern:

Be it known that I, FRED MATHEWS, a citizen of the United States, residing at Chicago, in the county of Cook and State of Illinois, have invented new and useful Improvements in Running-Board Retainers, of which the following is a full, clear, and exact description.

My invention relates to retainers for running-boards of box-cars, that is, to means for holding down the ends of said running-boards and securing the same to the saddles that support them.

The object of my invention is to provide simple means which will secure and hold the ends of the alining planks of the running-board to the saddle upon which they are supported without the necessity of nails or bolts, and thus keep the ends of the boards in alinement and at the same level, and avoid the presence of nail-heads and bolts, which, in the freight cars now in extensive use, work loose and project up above the upper surfaces of the planks and trip the brake-men and often times cause serious injuries to them for which the railroad companies have to pay. This I accomplish by the means hereinafter fully explained, and as particularly pointed out in the claims.

In the drawings: Figure 1 is a perspective view of my invention. Fig. 2 is a transverse section of the roof of a freight car showing my improved retainer applied thereto. Fig. 3 is a transverse section taken on dotted line 3—3, Fig. 2, and drawn to a larger scale. Fig. 4 is a perspective of a modified construction of my invention. Fig. 5 is a perspective view of yet another modification of the same.

Referring to the drawings, A represents the roof of a box-car, which may be constructed in any suitable manner; B represents the saddles for the running-board that are secured transversely in the usual manner over the ridge of the roof, and C represents the planks of the running-board.

My improved retainer consists of a rectangular tubular cast metal member having a bottom-plate *a*, the length of which is slightly greater than the width of the top of saddle B, and the width of which is slightly greater than the width of a plank of the running-board; a top-plate *c*, preferably, corresponding in dimensions to the bottom-plate *a*, and vertical side-walls *b* which connect said bottom and top-plate.

The transverse end edges of bottom-plate *a* are flanged downward and lap against the sides of the saddle and the ends of these flanges *d* project beyond side-walls *b*, *b*, and are, preferably, extended downward to form lugs *e*, *e*, which latter are provided with bolt holes through which the bolts *g* pass that secure the retainer to the saddle.

It is customary to use three parallel planks in each running-board, and to break the joints of alining planks so as to minimize the danger of tripping on the same.

My improved retainer can be utilized in cars where it is desired to thus break the joints of the planks, but it is unnecessary, when my invention is employed, to do so. I am, therefore, able to use the full lengths of the planks and to have the joints thereof over any one of the saddles supporting the running-board and secure them to said saddle by my improved retainers.

When the joints of the planks of the running-board are thus arranged in the same transverse plane, I prefer, as shown in Fig. 2 of the drawings, to slightly step lugs *e*, say, at the left hand side of the retainer laterally outward from the side of the saddle, and to depress the outer surface of the right hand side of the lugs *e* so that the lugs of one retainer can overlap the lugs of the other retainer, and thus secure the adjacent ends of adjoining retainers to the saddle by one bolt instead of two, which it would be necessary to employ were said retainers moved out of contact with each other.

In Fig. 4 of the drawings, I show a modification of my invention in which, instead of making the retainer tubular by using top-plate *c*, the longitudinal sides of the bottom-plate *a* are flanged upward and the upper edges of these flanges *d* are bent toward each other so as to provide overlying portions *4* that will lap over the side-edges of the ends of the planks and confine said ends and hold the joints securely within the embrace of the retainer. The transverse edges *5* of this modified retainer are flanged downward, the same as in the preferred form of my invention, and the ends of these downwardly flanged edges extend beyond the vertical plane of flanges *d* and are provided with lugs *6*, the construction of which corresponds to that of lugs *e* of the preferred form.

In Fig. 5 of the drawings, I show another modification, which consists of an angle-iron clip *7* the horizontal leg of which

is adapted to overlap the side edges of the ends of the plank. These clips are provided at each end with lugs 8, 8, that are made integral with and project laterally from the 5 lower corners of the vertical member of the angle-iron clip in a direction opposite to that from which the overlying horizontal portion of the same projects. One of these clips 7 is used on each side of the plank, 10 and lugs 8, 8, thereof are provided with openings 9 therein for the passage of the bolt that is used to secure the same to the saddle.

It will be noticed that the underside of 15 top-plate *c* of the preferred tubular form of my invention, next to side-walls *b* thereof, is beveled, and also that the underside of the overlapping portions of flanges 2 of the modification, shown in Fig. 5, are beveled. This is done so as to make the workman gain the retainers of the modified forms 20 into the ends of the running-board planks so that the upper surfaces of the horizontal overlying portions of the longitudinal sides 25 thereof will be flush with the upper surfaces of said planks, and so as to prevent the said planks from creeping or having longitudinal play. All that the car builder has to do is to bevel away the side edges of the 30 ends of the planks slightly, with a hatchet or any other suitable means, and thus shape the ends of said planks so that they can be easily inserted in the retainers.

These retainers may be made either of 35 cast metal, as shown in Fig. 2 of the drawings, or may be made of sheet metal, as shown in Fig. 5, and they may be secured to the saddles by either bolts or nails or spikes. Such changes I consider as coming 40 within the scope of my invention.

What I claim as new:

1. A retainer for the planks of the running-boards of a box-car comprising upwardly projecting longitudinal members 45 whose upper edges are provided with horizontal portions the undersides of which are beveled and are adapted to overlap the side edges of said planks, and downwardly projecting lugs that are adapted to be secured to the saddles supporting said running-boards. 50

2. A retainer for the planks of the running-boards of a box-car consisting of a plate having upwardly projecting longitudinal sides whose upper edges are provided with horizontal portions that project toward each other therefrom, and having transverse edges that are provided with downwardly projecting attaching members. 55

3. A retainer for the planks of the running-board of a box-car comprising a plate

having upwardly projecting longitudinal sides whose upper edges are provided with horizontal portions that project therefrom toward each other and having transverse edges that are provided with downwardly 65 projecting flanges the ends of which project beyond the longitudinal sides of said plate and are adapted to be secured to the saddle upon which said running-board is supported.

4. A retainer for the planks of the running-board of a box-car comprising a plate having upwardly projecting longitudinal sides whose upper edges are provided with horizontal portions that project therefrom toward each other and having transverse 75 edges that are provided with downwardly projecting flanges the ends of which project beyond the longitudinal sides of said plate and form lugs which at one end of said plate are separated more than those at the other and are adapted to be secured to the saddle upon which said running-board is supported.

5. A retainer for the planks of the running-board of a box-car comprising a rec- 85 tangular tubular retainer adapted to receive the ends of alining planks of said board and having its transverse edges flanged downward and adapted to be secured to the saddle upon which said running-board is sup- 90 ported.

6. A retainer for the planks of the running-board of a box-car comprising a rec- 95 tangular tubular retainer adapted to receive the ends of alining planks of said board and having its transverse edges flanged downward and the ends of said flanged portion extended beyond the longitudinal sides of the retainer, and adapted 100 to be secured to the saddle upon which said running-board is supported.

7. A retainer for the planks of the running-board of a box-car comprising a rec- 105 tangular tubular retainer, the underside of the portions of the top of the bore of which next the side-walls thereof being beveled or inclined downward, and adapted to receive the ends of alining planks of said board and having its transverse edges flanged downward and the ends of said flanged por-110 tion extended beyond the longitudinal sides of the retainer, and adapted to be secured to the saddle upon which said running-board is supported.

In witness whereof I have hereunto set my 115 hand this 5th day of October, 1916.

FRED MATHEWS.
